(57) **CLAIM**

The ornamental design for a table base, as shown and described.

DESCRIPTION

FIG. 1 is a front perspective view of a table base.

FIG. 2 is a front elevational view of the table base.

FIG. 3 is a right side elevational view of the table base.

FIG. 4 is a rear elevational view of the table base.

FIG. 5 is a left side elevational view of the table base.

FIG. 6 is a top plan view of the table base; and,

FIG. 7 is a bottom plan view of the table base.

The broken lines are for environmental purposes only and form no part of the claimed design.
